FUEL INJECTOR RACK SETTING MEANS
Alfonso G. Jordan, 879 Walnut St., San Jose, Calif.
Filed June 15, 1962, Ser. No. 202,780
8 Claims. (Cl. 103—37)

This invention relates to fuel injectors of the type employed in multi-cylindred diesel engines and more particularly to an improved injector rack setting means therefor.

The present invention is more particularly directed to an injector rack setting means for unit injectors of the type used in General Motors diesels and the like. The demand for more power and greater economy of operation and maintenance in diesel engines makes it most critical that fuel distribution to all cylinders be made as equal as possible.

In the General Motors two-cycle diesel engines, equal distribution of fuel injected per stroke of each injector is set by means of its rack and gear after the injectors are installed in the cylinder heads of the engine. Each rack is set at a pre-determined fixed measurement. For example, in the injectors utilized primarily in the railroad industry, the rack is set one inch from the end of the rack to the body of the injector with no way to compensate for unequal delivery due to wear of the plunger and/or spray tip assembly of the injector.

The present method of equalizing fuel delivery for a particular set of injectors to be used in an engine is accomplished by running each such injector in a bench type test stand to determine its output. For example, on the General Motors Model 567C, Needle Injector at one inch rack setting as explained above, 800 r.p.m. and 800 strokes p.m., the accepted delivery tolerance is from 424 to 440 ccs. In other words if all 16 injectors are within that range they are assumed to be as close to equal as is feasibly possible. This allows a latitude of a maximum of 16 ccs. differential between the least and greatest fuel delivery of a set of injectors.

If an injector is tested and found to deliver say 420 ccs., the present method of correcting this to get it into the desired range is to disassemble the injector and install a new plunger and bushing and/or an Old Tip Assembly with the holes worn sufficiently as not to allow too much back pressure so that more fuel will flow through at a given stroke. In other cases it may be necessary to install a new type gear that will advance the plunger helix a sufficient amount relative to the one inch setting of the rack to increase the output of a particular injector to the 424-440 cc. accepted range. Aside from the fact that some injectors will by chance fall into the accepted range, all others according to these methods will require that the injector be disassembled and the parts replaced and retested with the possibility that this operation will have to be repeated. There is still a great deal of guesswork and very little control over the increase or decrease of injector output. The prime expense of this method is an increase in inventory of injector parts, an increase of consumption of injector parts and additional labor and usage of the injector test stand.

It is an object of the present invention to alleviate the need for such extensive and time consuming changes and tests in order to equalize the fuel distribution of a particular set of injectors. In accordance with the present invention under the same conditions, assuming the injector was set with one inch rack setting at 800 r.p.m.'s and 800 strokes with a delivery of 420 ccs., it is contemplated that the appropriate adjustment of fuel flow within one cc. of delivery can be made without disassembling the injector or retesting the injector.

It is another object of this invention to provide a means

2

for varying the length of the rack to vary the port adjustment of the fuel intake to thereby increase and/or decrease the amount of fuel injected per stroke.

It is yet another object to provide a rack stroke adjusting means accessible to mechanics whereby compensation for fuel injection differences between injectors can be accomplished on the test stand.

These and other objects and advantages of the present invention will become apparent from a reading of the following description in the light of the drawings in which:

FIG. 1 is a detailed section (partially in elevation) of a General Motors diesel fuel injector with linkage for operating the same.

FIG. 2 is a fragmentary portion of FIG. 1 with parts thereof in a different position.

FIG. 3 is an enlarged longitudinal section of the right hand end of the rack bar of FIGS. 1 and 2.

FIG. 4 is an elevational view of FIG. 3 as seen from above therein.

FIG. 5 is an end elevation and partial section of FIG. 3 taken substantially along line 5—5 thereof.

The injector 10 shown in FIG. 1 consists of a forged steel, hollow body 11 in which is housed a high pressure pump 12 by which a measured quantity of fuel is forced into and through a spray nozzle 13 for discharge into the cylinder of a diesel engine (not shown).

The pump 12 consists of a bushing 14 so disposed in the hollow body 11 as to provide a somewhat cylindrical clearance space 15 between the bushing 14 and inner wall of the housing 11 to allow fuel oil to surround the bushing.

The housing 11 has an inlet passage 16 communicating with the cylindrical space 15 and with a fuel supply line or conduit 17 in a manner well known in the art.

A plunger 18 is arranged in an axial bore 19 in the bushing 14 for reciprocation therein by means of a spring loaded plunger follower 20 which extends upwardly exteriorly of the body 11 for operation by one end 21 of a rocker arm (not shown) synchronized with stroke of the cylinder of the diesel engine on which the injector 10 is installed.

As best seen in FIGS. 1 and 2 the bushing 14 has upper and lower ports 22 and 23 formed therein between the cylindrical space 15 and the pump bore 19 to admit fuel oil into the latter. The fuel oil is constantly present in the space 15 and under sufficient pressure to supply the demand of the pump 12, limited only by the stroke of the plunger 18 and a helical chamber or recess 25 formed on the plunger for periodic communication with the upper and lower ports 22 and 23.

Periodic communication of the helical recess 25 with the fuel admittance ports 22-23 is controlled by relative turning of the entire plunger 18 within the pump bore 19. The means for turning the plunger 18 includes a pinion gear 26 slidably arranged on the upper end of the plunger 18 in an area of confinement within the housing 11, the plunger and pinion gear having related flat surfaces, one of which is shown at 27 in FIG. 2 to assure turning of the plunger as it is reciprocated within the pump bore 19 of the bushing 14.

A rack bar 30 is arranged upon the housing 11 for reciprocation through the same tangentially of the pinion gear 26 so that the teeth 31 on the rack bar mesh with the gear 26 to turn the latter in accordance with the lateral strokes of the rack bar 30.

The present invention resides in means 35 for lengthening and/or shortening the rack bar 30 for changing the relative disposition of the helical chamber 25 on the plunger 18 relative to the upper and lower ports 22 and 23 respectively.

The means 35 (FIGS. 3, 4 and 5) includes a movable drive end 36 for the rack 30 having the conventional roller

37 mounted on a pin 38 which is sweat onto the end 36. The main body 32 of the rack 30 is drilled and tapped axially thereof as at 33 for receiving one end of a self locking screw shank 39 of an adjusting bolt 40. This bolt 40 has a headed end 41 disposed in an enlarged bore 42 in the drive end 36 of the rack, the screw shank 39 extending through a minor bore 43 for threaded connection in the tapped bore 33 of the main body 32 of the rack 30. As best seen in FIGS. 3 and 4 the roller carrying pin 38 extends diametrically across the bore 42 and has a transverse bore 44 formed therethrough in axial alignment with the rack 30 and its drive end 36. This provides an access opening from the open end 45 of the bore 42 to the head 41 of the adjusting bolt 40. This access opening is necessary for a hex-wrench W adapted to fit the hex-socket 46 in the head 41 of bolt 40. The wrench is the well known "Allen" head wrench W and bolt now so widely used.

The head 41 of the bolt 40 is disposed between the pin 38 and the shoulder 47 provided at the junction of the minor and major bores 43 and 42. A neoprene washer 48 is disposed between the head 41 of bolt 40 and the shoulder 47 to maintain the head 41 against the pin 38 and to prevent back lash when the head 41 is turned relative to the metal surface at the shoulder 47.

The shank 39 of the bolt 40 is of alloyed steel to likewise prevent galling of the metals when the bolt is turned to draw its head 41 and the drive end 36 of the rack toward the main body 32 thereof. The shank 39 of the bolt 40 has a "Nylock" insert 49 (FIG. 3) which expands against the inside threading in the main body 32 of the rack 30 to frictionally hold the screw shank in any adjusted position relative thereto. Upon turning of the screw bolt 40 by means of the "Allen head" wrench W the movable drive end 36 is moved toward and/or from the main body 32 of the rack 30 to change the relative position of the helical chamber 25 relative to the pump ports 22 and 23.

Since turning of the bolt 40 relative to the end 36 tends to change the position of the roller 37 with respect to its drive lever 50 means 51 is provided for maintaining the drive end 36 in correct position relative to the toothed surface 31 of the rack 30.

This means 51 comprises a pair of spring steel expansion pins 52 and 53 arranged in aligned bores in the main body 31 and the drive end 36 of the rack 30. The bores 54 and 55 in the main body 31 are diametrically opposite each other as are the bores 54' and 55' in the drive end 36. As best seen in FIG. 5, the pins 52 and 53 are identically C shaped in cross section and being precision made of spring steel tend to assume a slightly greater diameter than the bores into which they are to fit.

These pins are seated firmly in the bores 54 and 55 in the main body 31 and extend beyond the outer end thereof a length substantially comparable to that of the drive end 36 of the rack. The pins 52 and 53 serve to guide and support the drive end 36 in alignment with the main body 31 and to maintain the roller 37 in correct position for operation by its operating lever 50. The lever 50 rocks to and fro in timed relation with the engine in the usual manner to load the pump with fuel once in each cycle of the engine.

Referring to FIG. 1 it will be noted that when the plunger 18 is all the way up (withdrawn) relative to the bore 19 of the pump bushing 14, fuel is admitted into the bore 19 below the plunger via the lower port 23.

The plunger 18 has a relief port 56 formed axially thereof from its lower end to a T head cross port 57 which opens up into the recess chamber 25. By this arrangement when the plunger moves downwardly to compress the full charge of fuel oil below it, any excess fuel will surge up through relief port 56 and into the helical recess or chamber 25. This will occur as long as the chamber 25 is in communication with either the upper and/or the

lower ports 22-23. However, once these ports 22 and 23 are cut off from the chamber 25, the charge of fuel oil beneath the plunger is compressed sufficiently to overcome a spring loaded check valve 60 (dotted lines FIG. 1) so that the charge of fuel will be squirted out the nozzle end 13 of the injector body. It will thus be appreciated that the position of the recess chamber 25 relative to the ports 22-23 as determined by the stroke of the rack 30 is very critical.

By the arrangement of this invention the rack 30 can be set at any desired position of adjustment to prolong or shorten the period of communication of the helical chamber 25 with the fuel intake phase of the operation of the injector and thereby increase or decrease the amount of fuel injected per stroke. In other words, turning of the screw bolt 40 to lengthen the rack 30 will increase the output of fuel and by tightening the screw into the tapped bore 33 the output of fuel will be decreased.

With the rack adjusting feature of the present invention the several injectors on an engine can all be calibrated to any output of fuel within one cc. Moreover, this can be done on the test stand, i.e., with assurance that the injector will admit fuel well within the allowed limits.

In this manner, injectors which might otherwise be discarded will be saved and the life of injectors can be prolonged with assurance of uniform, i.e., equalized fuel injectors on all cylinders.

While I have described my invention in specific detail it will be appreciated by those skilled in the art that the same may be susceptible to variations, alterations and/or modifications without departing from the spirit of my invention. I therefore desire to avail myself of all variations, alterations and/or modifications of structure which may reasonably come within the purview of the following claims.

What I claim as new and desire to protect by Letters Patent is:

1. In a fuel injector including a pump in which a pump plunger reciprocable within the injector body has a helical recess communicable with fixed fuel inlet ports in the injector body, and an injector rack having its toothed main body meshing with a pinion gear on said plunger and its drive end engaged by a rocker arm for moving said rack axially to and fro to turn the plunger while the latter reciprocates for maintaining said helical recess in communication with at least one of the fixed ports for a period of time sufficient to load said pump with a predetermined quantity of fuel; an injector rack setting means comprising a separate drive end on said body having a rocker arm engaging roller on one side thereof, a pin on said roller projecting diametrically through the drive end of said rack, said drive end having a major bore and a minor bore the latter facing said main body of the rack and in axial alignment therewith, a screw shank extending through said minor bore, said screw shank having a head portion within said major bore and engaging said pin, a tapped axial bore in the main body of said rack for receiving the threaded end of said screw shank, and an access bore diametrically through said pin in axial alignment with said major bore facilitating admittance of a tool to the head of said screw shank for turning the same to lengthen and shorten the rack to thereby change the period of communication of said recess with one or both of said ports.

2. In a fuel injector including a pump in which a pump plunger reciprocable within the injector body has a helical recess communicable with fixed fuel inlet ports in the injector body, and an injector rack having its toothed main body meshing with a pinion gear on said plunger and its drive end engaged by a rocker arm for moving said rack axially to and fro to turn the plunger during its reciprocation for maintaining said helical recess in communication with at least one of the fixed ports for a period of time sufficient to load said pump with a pre-

determined quantity of fuel; an injector rack setting means comprising a separate drive end on said body having a rocker arm engaging roller on one side thereof, a pin on said roller projecting diametrically through the drive end of said rack, said drive end having a major bore and a minor bore the latter facing said main body of the rack and in axial alignment therewith, a screw shank extending through said minor bore, said screw shank having a head portion within said major bore and engaging said pin, a tapped axial bore in the main body of said rack for receiving the threaded end of said screw shank, an access bore diametrically through said pin in axial alignment with said major bore facilitating admittance of a tool to the head of said screw shank for turning the same to lengthen and shorten the rack to thereby change the period of communication of said recess with one or both of said ports, and means offset radially from the screw shank in said main body of said rack and extending into said drive end thereof for resisting turning of the latter relative to said main body during turning of said screw to thereby maintain said roller in correct position to engage said rocker arm.

3. In a fuel injector including a pump in which a pump plunger reciprocable within the injector body has a helical recess communicable with fixed fuel inlet ports in the injector body, and an injector rack having its toothed main body meshing with a pinion gear on said plunger and its drive end engaged by a rocker arm for moving said rack axially to and fro to turn the plunger as the plunger reciprocates for maintaining said helical recess in communication with at least one of the fixed ports for a period of time sufficient to load said pump with a predetermined quantity of fuel; an injector rack setting means comprising a separate drive end on said body having a rocker arm engaging roller on one side thereof, a pin on said roller projecting diametrically through the drive end of said rack, said drive end having a major bore and a minor bore the latter facing said main body of the rack and in axial alignment therewith, a screw shank extending through said minor bore, said screw shank having a head portion within said major bore and engaging said pin, a tapped axial bore in the main body of said rack for receiving the threaded end of said screw shank, an access bore diametrically through said pin in axial alignment with said major bore facilitating admittance of a tool to the head of said screw shank for turning the same to lengthen and shorten the rack to thereby change the period of communication of said recess with one or both of said ports, said main body and said drive end thereof having diametrically opposed aligned bores extending parallel to the axis of said screw shank, and an expansion pin extending into each set of said diametrically opposed bores for maintaining said main body and drive body against relative rotation during turning of said screw shank and for guiding said drive end of said rack during movement thereof toward and from said main body during turning of said screw shank.

4. In combination with an injector rack having a toothed portion meshed with pinion gear on a fuel pump the plunger of which has an helical recess communicable with fuel inlet ports for admitting a pre-determined quantity of fuel to said pump; an injector rack setting means comprising a separate drive end on the toothed portion of said rack having a rocker arm engaging roller on one side thereof, a pin on said roller projecting diametrically through the drive end of said rack, said drive end having a minor bore at one end facing the toothed portion of said rack and in axial alignment therewith, said drive end having a major bore at its opposite end providing a shoulder at the juncture of said minor bore, a headed screw having its shank extending through said minor bore and its head portion within said major bore between said shoulder and said pin, a tapped axial bore in the toothed portion of said rack for receiving the threaded end of said screw shank, and an access bore diametrically

through said pin in axial alignment with said major bore facilitating admittance of a tool to the head of said screw shank for turning the same to lengthen and shorten the rack and thereby change the position of the helical recess on said plunger relative to said ports.

5. In combination with an injector rack having a toothed portion meshed with pinion gear on a fuel pump the plunger of which has an helical recess communicable with fuel inlet ports for admitting a predetermined quantity of fuel to said pump; an injector rack setting means comprising a separate drive end on the toothed portion of said rack having a rocker arm engaging roller on one side thereof, a pin on said roller projecting diametrically through the drive end of said rack, said drive end having a minor bore at one end facing the toothed portion of said rack and in axial alignment therewith, said drive end having a major bore at its opposite end providing a shoulder at the juncture of said minor bore, a headed screw having its shank extending through said minor bore and its head portion within said major bore between said shoulder and said pin, a tapped axial bore in the toothed portion of said rack for receiving the threaded end of said screw shank, an access bore diametrically through said pin in axial alignment with said major bore facilitating admittance of a tool to the head of said screw shank for turning the same to lengthen and shorten the rack and thereby change the position of the helical recess on said plunger relative to said ports, said toothed portion and said drive end of said rack having diametrically opposed aligned bores extending parallel to the axis of said screw shank, and an expansion pin extending into each set of said diametrically opposed bores for resisting relative turning of the toothed portion and the drive end of said rack during turning of said screw shank and for guiding said drive end of said rack during movement thereof toward and from said toothed portion during turning of said screw shank.

6. In an injector rack having a main rack body provided with a toothed portion engaging a pinion gear slideable on the plunger of a pump for turning said plunger to position an helical recess thereon in communication with fuel ports for a predetermined time during each stroke of such plunger, a rack setting means comprising a separate drive end on said main body having a rocker arm engaging roller on one side thereof, a pin on said roller projecting diametrically through said drive end, said drive end having an axial minor bore at one end and a major bore at its opposite end providing a shoulder within said drive end, a screw shank extending through said minor bore, said screw shank having a head portion within said major bore engaging said shoulder and said pin for moving the drive end with said screw shank, a tapped axial bore in said main body for receiving the threaded end of said screw shank, and an access bore diametrically through said pin in axial alignment with said major bore facilitating admittance of a tool to the head of said screw shank to turn the same to lengthen and shorten the rack for prolonging and diminishing the time of communication of the helical recess on said plunger with the fuel ports during each stroke of said plunger.

7. In an injector rack having a main rack body provided with a toothed portion engaging a pinion gear slideable on the plunger of a pump for turning said plunger to position an helical recess thereon in communication with fuel ports for a predetermined time during each stroke of such plunger, a rack setting means comprising a separate drive end on said main body having a rocker arm engaging roller on one side thereof, a pin on said roller projecting diametrically through said drive end, said drive end having an axial minor bore at one end with a major bore at its opposite end providing a shoulder within said drive end, a screw shank extending through said minor bore, said screw shank having a head portion within said major bore engaging said shoulder

der and said pin for moving the drive end with said screw shank, a tapped axial bore in said main body for receiving the threaded end of said screw shank, an access bore diametrically through said pin in axial alignment with said major bore facilitating admittance of a tool to the head of said screw shank to turn the same to lengthen and shorten the rack for prolonging and diminishing the time of communication of the helical recess on said plunger with the fuel ports during each stroke of said plunger, and means for guiding said drive end for non-turning movement toward and from said main body during turning of said screw.

8. In an injector rack having a main rack body provided with a toothed portion engaging a pinion gear slideable on the plunger of a pump for turning said plunger to position an helical recess thereon in communication with fuel ports for a predetermined time during each stroke of such plunger, a rack setting means comprising a separate drive end on said main body having a rocker arm engaging roller on one side thereof, a pin on said roller projecting diametrically through said drive end, said drive end having an axial minor bore at one end and a major bore at its opposite end providing a shoulder within said drive end, a screw shank extending through said minor bore, said screw shank having a head portion within said major bore engaging said shoulder and said pin for moving the drive end with said screw shank, a tapped axial bore in said main body for receiving the

5 threaded end of said screw shank, an access bore diametrically through said pin in axial alignment with said major bore facilitating admittance of a tool to the head of said screw shank to turn the same to lengthen and shorten the rack for prolonging and diminishing the time of communication of the helical recess on said plunger with the fuel ports during each stroke of said plunger, means for guiding said drive end for non-turning movement toward and from said main body during turning of 10 said screw comprising diametrically opposed aligned bores in said main body and said drive end extending parallel to the axis of said screw shank, and an expansion pin extending in each of said diametrically opposed bores in said main body and into the diametrically opposed bores in said drive end for frictionally sliding movement relative thereto as said drive end moves toward and from the main body of said rack during turning of 15 said screw shank.
